UNITED STATES PATENT OFFICE.

GEORGE NELSON BROATCH, OF MOOSE JAW, SASKATCHEWAN, CANADA.

PIPE.

Application filed October 18, 1919. Serial No. 330,164.

To all whom it may concern:

Be it known that I, GEORGE N. BROATCH, a subject of the King of Great Britain, residing at Moose Jaw, in the Province of Saskatchewan and Dominion of Canada, have invented new and useful Improvements in Pipes, of which the following is a specification.

This invention relates to smokers' pipes, 10 and has for an object the provision of a pipe in which the particles of tobacco and the moisture from the bowl are prevented from passing into the mouth of the smoker.

Another object is the provision of a pipe 15 having a chamber for the collection of tobacco particles or moisture, in which there is provided a novel form of screen or perforated hollow cone positioned between the bowl and mouth piece for the purpose of 20 preventing the passage of the said particles or moisture through the stem, thereby providing a sufficient condensation of the moisture in the smoke so as to prevent any moisture from coming through to the mouth of 25 the smoker.

Another object is the provision of a pipe possessing the different characteristics, which is simple of construction and which may be easily taken apart and reassembled 30 for the purpose of cleaning.

Another object is the provision of a novel form of screen or perforated cone which may vary in size or shape to suit or fit various forms of manufactured smokers' pipes, 35 some of which may require minor changes to admit the said screen or cone, the screen cone or filter beside providing an absolute elimination of all particles of dirt or other deleterious material, is formed of a perforated metal or wire screen which will permit 40 of its use indefinitely, and will obviate the necessity of carrying or purchasing means for replenishing or cleaning the filter as is customarily required.

Other objects and advantages of the invention will appear as the following description is read in connection with the accompanying drawings.

In the drawings:

Figure 1 is a longitudinal sectional view of a pipe embodying the present invention.

Figure 2 is an enlarged fragmentary section of a portion of the stem.

Figure 3 is a detail perspective view of 55 the perforated hollow cone or screen.

Referring to the drawings, wherein like characters of reference denote corresponding parts, the bowl of the pipe is indicated at 10 and the stem at 11. The latter is formed in sections 12 and 13, the former being carried by the bowl and the latter forming the mouth piece of the pipe. These sections are joined together by forming the mouth piece with a reduced portion or nipple 14, which enters the adjacent end of the section 12 and 60 may be either a slip joint or a push joint, or may be threadedly secured therein, as desired.

The extremity of the nipple 14 is further reduced, as indicated at 15, and this reduced 70 portion is adapted to receive the cylindrical base of the screen or perforated cone 16 which in the present disclosure, for illustrative purposes, is shown as composed of a wire screen, it of course being obvious that 75 the filter could be in the form of a perforated metal cone as well as the screen structure disclosed; the base of the said screen or cone is adapted to be varied in diameter, depending upon the size of the shoulder 80 15. As will be noted, the screen or cone has its tapered end projecting toward the bowl of the pipe, as shown. The screen is located within an enlarged portion of the bore of the stem, which forms a collecting 85 chamber 17, which receives particles of tobacco or moisture drawn from the bowl. This chamber communicates with the bowl through the medium of a passage 18, which is preferably located adjacent the bottom 90 of the chamber. By forming the screen or perforated cone 16 in the manner shown, an obstructed passage for the smoke is always provided through the bore of the stem, as in the event of any of the particles of tobacco 95 resting upon the surface of the screen or cone, the smoke may freely pass through the openings upon the lower surface.

A further advantage in providing the perforated metal cone or screen with a conical 100 or tapered closed end resides in providing a baffled passageway from the bowl to the mouthpiece of such a formation that the nicotine collecting on the perforated metal cone or screen will be carried down to the 105 point or forward end of the filter and there be dropped off into the chamber 17 and whatever moisture in the form of nicotine or otherwise which may be retained on the inside of the perforated metal cone or screen 110

may be readily ejected by lightly tapping it point downward when the mouthpiece is removed from the bowl stem or blown out by the smoker when the mouthpiece is so removed.

The invention is susceptible of various changes in its form, proportions and minor details of construction and the right is herein reserved to make such changes as properly fall within the scope of the appended claim.

Having described the invention, what is claimed is:

A pipe comprising a bowl and a sectional

stem, said stem being formed with an enlarged chamber communicating with the 15 bowl through a constricted opening in the inner wall of said chamber, said mouth piece provided at its inner end with a reduced shoulder, and a hollow cone-shaped perforated metal or wire screen having its enlarged end engaging said reduced shoulder, and its tapered end extending within the chamber for the purpose specified.

In testimony whereof I affix my signature.

GEORGE NELSON BROATCH.
